ATOMIZER CASE

Filed Oct. 20, 1936

FIG. 1

FIG. 2

FIG. 3

Inventor:

George W. Blow

UNITED STATES PATENT OFFICE

105,566

DESIGN FOR AN ATOMIZER CASE

George W. Blow, New York, N. Y.

Application October 20, 1936, Serial No. 65,383

Term of patent 7 years

To all whom it may concern:

Be it known that I, George W. Blow, a citizen of the United States and resident of New York city, in the county of New York and State of New York, have invented a new, original, and ornamental Design for an Atomizer Case, of which the following is a specification, reference being had to the accompanying drawing, forming a part thereof.

In the drawing Figure 1 is a front elevational view of an atomizer case showing my new design; Figure 2 is a top plan view thereof; and Figure 3 is a side elevation thereof.

I claim:

The ornamental design for an atomizer case, substantially as shown.

GEORGE W. BLOW.
